United States Patent Office

Des. 186,987
Patented Jan. 5, 1960

186,987

TOY CROSS-BOW

Denis A. Dickinson, Southport, England, assignor to
Ewart Neville Dickinson, David Richmond Dickinson,
and John Alexander Dickinson

Application July 29, 1959, Serial No. 56,992

Term of patent 14 years

(Cl. D34—15)

Fig. 1 is a perspective view of a toy cross-bow, showing the front and one side thereof;

Fig. 2 is a reverse perspective view showing the other side and the rear thereof;

Fig. 3 is a corresponding side elevation.

I claim:

The ornamental design for a toy cross-bow, substantially as shown.
